TRAY OR SIMILAR ARTICLE

Robert L. Gruen, New York, N. Y., assignor to
Continental Silver Co. Inc., a corporation of
New York

Application November 15, 1951, Serial No. 17,422

Term of patent 14 years

(Cl. D44—10)

To all whom it may concern:

Be it known that I, Robert L. Gruen, a citizen of the United States and residing at New York, in the county of New York and State of New York, have invented a new, original, and ornamental Design for Tray or Similar Article, of which the following is a specification, reference being had to the accompanying drawings, forming part thereof, and in which

Fig. 1 is a perspective view of a tray or similar article, showing by new design,

Fig. 2 is a top plan view,

Fig. 3 is a side elevational view, and

Fig. 4 is a vertical transverse sectional view thereof taken along line 4—4 of Fig. 2.

The dominant feature of my design resides in

the grooved inlay ornamentation placed along a diameter of the tray, as shown.

I claim:

The ornamental design for a tray or similar article, substantially as shown and described.

ROBERT L. GRUEN.
